UNITED STATES PATENT OFFICE.

WILLIAM H. CAMPBELL, OF ALBION, NEW YORK.

WIRE-FENCE MACHINE.

SPECIFICATION forming part of Letters Patent No. 567,123, dated September 8, 1896.

Application filed December 2, 1895. Serial No. 570,834. (No model.)

To all whom it may concern:

Be it known that I, WILLIAM H. CAMPBELL, of Albion, in the county of Orleans and State of New York, have invented a certain new and useful Improvement in Wire-Fence Machines; and I do hereby declare that the following is a full, clear, and exact description of the same, reference being had to the drawings accompanying this application.

10 My improvement relates to machines for making wire fence in the field.

It also relates to that class in which a series of gears are used corresponding in number with the number of longitudinal strands in 15 the fence, and a set of twister-heads are used, being movable from one gear to another by reversely-acting slides.

The invention consists in the combination and arrangement of parts hereinafter described and claimed.

In the drawings, Figure 1 is a front elevation of the machine, looking in the direction of arrow 1, Fig. 3. Fig. 2 is a side elevation looking in the direction of arrow 2, Fig. 3. Fig. 3 is an enlarged cross-section in line xx of Fig. 1. Fig. 4 is an enlarged side elevation of one of the gears and the connecting twister, looking in the direction of arrow 2 in Fig. 3. Fig. 5 is an end elevation of Fig. 4, looking 30 in the direction of arrow 3 of the last-named figure.

A indicates the standard or frame of the machine attached to a base having trucks which run on a platform in the usual manner. B B B B are a series of spur-gears attached thereto and engaging together, their number corresponding with the number of longitudinal strands $a a$ of the fence. These wires $a a$ pass through the center of the wheels and 40 through tubes $b b$ in the usual manner. One of these gears B has a bevel-gear B', with which engages a bevel-pinion C, Fig. 3, resting on a cross-shaft c and provided with a crank d, by which it is operated. By this means all 45 the gears are operated at once. The face of each of the spur-gears B has two parallel flanges ff , which form guides for the inner ends of the twister-frames, as will presently be described. In the position for shifting the 50 twisters from one gear to another these flanges stand vertically and in alinement in all the wheels. Each of the gear-wheels also has a

large rectangular guide-frame D rigidly attached thereto and projecting outward at right angles, said frame consisting of upper 55 and lower horizontal bars $g g$ and a vertical connecting outer cross-bar h , the latter having flanged circular ribs $h' h'$ at its edges, as shown in the plan view, Fig. 3. The frames D serve as guides and holders for the twister- 60 frames as they pass from one gear to another.

E E are the twister-frames, the same being large, flat-sided, and of rectangular form and fitting the flat sides of the guide-frames just described. The twister-frames are arranged 65 to slide up and down on opposite sides of the guide-frames. The inner ends of the twister-frames E have bearings ii , which rest inside the guide-flanges ff on the faces of the gears. To the outer ends of the twister- 70 frames are attached the twister-heads E' E', each consisting of a segment approximating a half-circle, standing at right angles to the frame and provided with a beveled groove k for receiving the curved edge of the bracket 75 by which the twister is raised or lowered. The twister-heads also have concave bearings jj , which slide up and down on the circular ribs $h' h'$ of the guide-frames D, by which means the outer ends of the twister-frames 80 are retained in place. If desired, the connection may be reversed, the brackets being grooved and the twister-heads having bearings to fit therein. Said twister-heads are also provided with outwardly-projecting lugs 85 ll , Fig. 3, pierced with holes, through which pass the filling-wires from the spools F F, said filling-wires also passing through the twister-heads themselves. The spools F F rest on studs $m m$, projecting from the sides of the 90 twister-frames, and tension thereon is produced by springs $n n$ or by other means.

G G are arms attached to the main standard A, projecting outward on each side and provided at their outer ends with bearing-blocks 95 $p p$, which form guides to the reversely-operating slides H H, which carry the twister-heads up and down. Said slides consist of long bars which slide between arms $p' p'$ of the guides $p p$. To the slides are attached 100 the brackets I I, which hold the twister-heads. The inner edges of the brackets are concaved to fit the circle of the twister-heads, by which means the twister-heads are allowed to revolve

freely between the brackets, but are carried up and down by the brackets as the slides are moved. Where an odd number of gears is used, as shown in the drawings, the upper bracket I' on one side and the lower on the other side are fixed and stationary, their only purpose being to furnish a guide for the single twister-head to turn in when thrown out to its farthest extent.

10 K is the ordinary rock-lever, with which the two operating-slides H H are connected to receive reverse movements. In ordinary machines now in use the slides are connected with the rock-lever by simple connecting rods or pitmen attached by pivots at both ends. Instead of such arrangement I employ on each side a bearing L, fast to the slide and provided with two forked ends s s, through which passes the connecting-rod t, attached to 20 the end of the rock-lever. On the lower end of the rod t are two nuts u u, by which means the bearing L, with the slide attached, can be raised and lowered. The object of this arrangement is to adjust the slide H up or 25 down to bring the two brackets in true alignment with each other, so that the twister-head will turn properly between them. Heretofore difficulty has been experienced in keeping the brackets in coincidence, so that the 30 twister-heads will turn easily, owing to the loose connections of the pitmen to the slides. By the means above described they can be adjusted with great accuracy and with little trouble.

35 A special feature of this invention is the rectangular guide-frame D, of large size, projecting bodily outward from the face of each

gear and forming a broad surface, on which the twister-frame E slides, the latter also being large and having a broad bearing-surface 40 to fit the guide-frame. By this means so broad a bearing-surface is attained that the twisters are held firmly to place during their rotation, and the filling-wires are wound under strain without danger of the twisters 45 cramping or yielding under action. The action is much more effective than in those machines where the bearing of the twister against its support is of small size. This broad bearing of the twister-frame enables it to move 50 up and down in a true line, thereby shifting from one wheel to another without striking any impediment or binding.

Having described my invention, what I claim as new, and desire to secure by Letters 55 Patent, is—

In a wire-fence machine, the combination, with the gears B B and reversely-operating slides H H, of the rectangular guide-frames D D projecting bodily from the gears, and 60 the corresponding rectangular twister-frames E E resting in contact therewith, and having twister-heads at their outer ends, the guide-frames provided with the flanged ribs h' h', and the twister-heads with bearings j j fitting over said ribs, as shown and described 65 and for the purpose specified.

In witness whereof I have hereunto signed my name in the presence of two subscribing witnesses.

WILLIAM H. CAMPBELL.
